INVENTOR.

Alfred M. Jacobson

UNITED STATES PATENT OFFICE

137,168

DESIGN FOR A KNIFE AND SCISSORS GRINDER GUIDE PLATE

Alfred M. Jacobson, Denver, Colo.

Application October 9, 1943, Serial No. 111,326

Term of patent 14 years

To all whom it may concern:

Be it known that I, Alfred M. Jacobson, a citizen of the United States, residing in the city and county of Denver and State of Colorado, have invented a new, original, and ornamental Design for a Knife and Scissors Grinder Guide Plate, of which the following is a specification, reference being had to the accompanying drawing, forming part thereof.

Figure 1 is a side elevational view of a knife and scissors grinder guide plate embodying my new design; and Figure 2 is a perspective view thereof.

I claim:

The ornamental design for a knife and scissors grinder guide plate, as shown.

ALFRED M. JACOBSON.
